UNITED STATES PATENT OFFICE.

FRANK B. WIDMAYER, MICHAEL E. TOEPEL, AND ADOLPH POTDEVIN, OF NEW YORK, N. Y.

GENERATOR OR MIXING VALVE.

SPECIFICATION forming part of Letters Patent No. 714,982, dated December 2, 1902.

Application filed May 9, 1901. Serial No. 59,379. (No model.)

To all whom it may concern:

Be it known that we, FRANK B. WIDMAYER, MICHAEL E. TOEPEL, and ADOLPH POTDEVIN, citizens of the United States, and residents of 5 New York city, in the county of New York and State of New York, have invented certain new and useful Improvements in Generator or Mixing Valves, of which the following is a specification.

10 Our invention relates to the construction of a generator or mixing valve suitable for use for automobile, marine, or other engines of the internal-combustion type and designed to furnish to the cylinder of the engine a quantity of combustible mixture formed at each stroke of the valve by commingling a fixed quantity of gasoline or other oil with air or other gas.

15 Our invention relates more particularly to that type of generator or mixing valve wherein the gasoline or other oil is supplied at each stroke of the main admission-valve through a supplementary valve hereinafter termed the "oil-valve," which opens a passage leading 20 from the oil or gasoline supply to a chamber into which the air is drawn by suction or vacuum produced by the piston of the motor.

The object of our invention is to furnish a simple, reliable, and compact mixing-valve 25 adapted to supply a fixed or invariable proportion of air and oil in the charge at any speed of the engine to which the valve is attached.

A further object of the invention is to eliminate the danger of flooding from a too-free 30 supply of oil and also to permit the proportion of air and oil to be easily regulated and to secure other advantages which will be more apparent from the subjoined description.

40 Our invention consists in the combinations of devices and details of construction more particularly hereinafter described and then specified in the claims.

One of the features of our invention resides 45 in the combination of a main admission-valve and an oil-valve positively coupled or connected with one another in the closing movement of the main valve, so that the oil-valve shall be seated by the positive action of the 50 main valve in the closing movement, but capable of movement independently of one another

in the opening movement of the valve, so that the main valve may move freely to open the main admission-ports, although the oil-valve may in the course of such reverse movement 55 be brought to rest. In carrying out this feature of our invention we use for the main admission-valve a type of valve that may be briefly described as being of the "slide-valve" type. 60

Another feature of our invention consists in the combination, with the oil-valve actuated by the main admission-valve, of a spring tending constantly to unseat said valve, thereby insuring the opening of said oil-valve when 65 the main admission-valve is opened by the suction or vacuum produced by the piston of the engine.

Another part of our invention consists in the combination, with the oil-valve and a main 70 admission-valve positively coupled thereto in the closing movement, but capable of movement independently thereof in the opening movement of the valve, of means for regulating the throw or travel of the oil-valve during 75 its opening stroke to adjust the amount of oil supplied at each charge.

Our invention consists also in means, as hereinafter described, for securing a finer regulation in the quality of the mixture and 80 for bringing about a more thorough mixture of the oil and the air.

In the accompanying drawings we show one of the forms of generator or mixing valve embodying our invention. 85

Figure 1 is a vertical central section through the device. Fig. 2 is a horizontal section on the line 1 1 of Fig. 1. Fig. 3 is a horizontal section on the line 2 2 of Fig. 1. Fig. 4 illustrates a modification in the form of valve 90 casing or body and the dispositions of the means for adjusting the throw of the oil-valve.

1 is the body or casing of the apparatus furnished at one end with a nipple 2, adapted for coupling to a pipe leading from the gasoline or oil supply and having a central outlet or passage 3, through which the oil is delivered to an orifice controlled by a suitable valve 4, which constitutes the oil valve or check and which may be of any desired form, but is preferably made as a needle-valve, and also by preference is provided with a spread-

ing or flaring body or surface below the outlet of pipe 3 to more thoroughly spread and distribute the oil admitted into the chamber 5. At the opposite end of the valve chamber 5 or casing is the outlet 6, through which the charge is delivered to the pipe leading to the cylinder of the engine.

The casing 1 may be of cylindrical form, and the end carrying the nipple 2 may be reduced 10 in diameter, as shown, at the portion where the chamber 5 is located. The outlet 6 may be formed in a base-piece 7, which may be coupled to the main body 1 by a screw-joint, as shown.

15 9 indicates a spider or diaphragm, which may be clamped between the piece 7 and the shoulder on the inside of the cylindrical portion 1 of the valve-casing, as shown.

The spider or frame 9 may serve to support 20 the parts of the main admission-valve, as will be presently described.

25 At 10 are shown a number of air-openings which admit air to the chamber 5, whence the air is drawn, commingled with the oil admitted by valve 4, to the mixing-chamber 11. From the latter the mixture passes through openings 12 to a supplemental mixing-chamber 13, and from the latter it passes through the spider or diaphragm 9 to the chamber 14, 30 whence it is delivered through the outlet 6 to the engine-cylinder.

35 The openings 12 are formed in the offset or shoulder between the main casing 1 and the reduced cylindrical portion in which the chamber 5 is located, and the imperforate portions in said shoulder or offset partly obstruct the flow of the mixture, so as to aid in securing a more thorough commingling of the air and oil vapors. This action may be 40 further enhanced by the obstructive effect of the spider or diaphragm 9.

45 The passage between the chamber 5 and the chamber 11 is controlled by the main admission-valve, which is opened by the suction of the engine-piston. This main admission-valve (indicated at 15) is constructed as a slide-valve, as shown, and when in the position indicated in Fig. 1 closes ports or openings formed in the wall of the casing or cylinder 50 in which it slides, said ports or openings constituting those through which the commingled oil and air are allowed to pass into the mixing-chamber 11.

55 The stem 16 of the valve 15 is guided, as shown, upon the stem rising from the spider or frame 9 or in any other suitable way. A spring 18, bearing at one end against the spider 9 and at the other against the lower side of the valve 15, tends to close and keep 60 the same closed.

65 The valve 15 operates upon valve 4 through a positive connection of any desired shape or form adapted to cause the valve 4 to be seated by a positive action, but to permit the valve 15 to move independently of valve 4 on the reverse movement, by which the valve 15 opens its ports. This positive connection

may be afforded by a shoulder on the valve 4, seated upon the top of the piston, as shown, so that said valve will be closed and held 70 closed by the positive action of the valve 15, actuated by its spring. This closing movement will obviously be always effectual, because the movement of the valve 15 is unobstructed by its own valve-seat, as would be 75 the case if it were the ordinary form of conical or similar valve, such as is frequently employed in generator or mixing valves. When the valve 15 is drawn down by the exhaust or relief of pressure within the chamber 80 13, the valve 4 is permitted to open the oil-supply simultaneously with the opening of the ports controlled by the main admission-valve 15. In the opening movement of the valve 4 it is obviously free from positive 85 connection with valve 15, and said valve 15 may move to any extent irrespective of the extent of movement of valve 4, which drops under the effect of gravity assisted, preferably, by a suitable spring.

90 The valve 4 has a stem 19, as shown, which passes down within the stem of valve 15 and is adapted on the downstroke to engage with a stop or check rod 20, adjustably mounted in the frame or spider 9. The rod 20 may be a screw adjustable, as shown, and provided with a check-nut 21 for holding it in adjusted position. As is obvious, by adjusting the rod 20 the travel of the valve 4 and the extent of opening of the orifice through which the oil 100 flows into the chamber 5 may be regulated. If the rod 20 is adjusted upwardly, the valve 4 is permitted to follow the valve 15 to a less distance, and hence a less quantity of oil will be injected into the chamber 5 at each stroke of 105 valve 15. The latter obviously will open to its full extent, no matter what the adjustment of the rod 20, and hence the action of the regulating-valve may be changed or adjusted without changing the tension of the spring for 110 the main regulator-valve or disturbing the action of said valve in any manner. When the valve 15 closes, the valve 4 is seated positively and in fact acts as a stop to limit the upward throw of the valve 15, inclosing the admission- 115 ports.

120 For the purpose of carrying the valve 4 down by a positive action and insuring the prompt and full opening of the same when the piston-valve opens we prefer to provide a supplemental spring 22, bearing at one end against the piston-valve 15 and at the other against a collar 23, secured to the valve-stem 19.

125 The spring 22 exerts a constant pressure or effect, tending to unseat the valve 4; but inasmuch as it is a weaker spring than 18 this effect is overcome by the superior action of the spring 18, which holds the valve 4 seated until the suction of the engine-piston opens 130 valve 15.

135 The mixing-chamber 11 may be formed by a supplemental cap or shell 24, concentric with the main admission-valve and having a

skirt or flange which extends down over the cylindrical portion 1 of the valve-casing and is adapted to slide freely thereon, if desired.

The shell 24 may form a part of or be attached to a collar or ring 25, which is adjustable by means of a screw-thread attachment upon the outside of the chamber 5, so that the skirt or flange may be moved up or down upon the body 1, and thereby regulate the size of supplemental air-openings 26, through which an additional air-supply may be admitted to the chamber 11 additional to that introduced with the oil from chamber 5 through the ports controlled by the slide-valve 15. By using this additional air-supply and adjusting it by any suitable device—such, for instance, as that shown—we are able to get a much finer regulation of the quality of the mixture. In the modification illustrated in Fig. 4 the outlet 6 is formed in the side of the base-piece 7, and the adjusting-stop 20 is mounted in the base 7 and is furnished on the outside with a thumb piece or disk 30, in conjunction with which a suitable index 31 may be employed to show or indicate the adjustment of the oil-valve. The valve-stem 19 in this case extends down through the spider or frame 9, as indicated, so as to engage the end of the adjustable stop 20.

30 What we claim as our invention is—

1. In a generator or mixing valve, the combination of an oil-valve and a main admission-valve positively engaged or connected therewith in its closing movement but capable of movement independently thereof in its reverse or opening movement.

2. In a generator or mixing valve, the combination with a main admission-valve, of an oil-valve positively engaged or actuated thereby in the closing movement but free from positive connection therewith during the opposite movement, and a stop for limiting the throw of the oil-valve during the reverse or opening movement as and for the purpose described.

45 3. The combination with the main admission-valve and an oil-valve actuated thereby, of a spring tending to open said oil-valve.

4. In a generator or mixing valve, the combination substantially as described, of a piston-valve controlling the admission of air and oil to a mixing-chamber, an oil-valve having a valve-seat adapted to stop the throw thereof in closing off the supply of oil said oil-valve being positively actuated or engaged by said piston-valve during closing movement but free from positive connection therewith during the reverse movement, and an adjustable rigid stop or abutment adapted to 55 be engaged by the oil-valve to positively limit the extent of opening movement thereof.

5. In a generator or mixing valve, the combination of a slide-valve, an oil-valve positively engaged by the slide-valve during its closing movement, a spring operating on the slide-valve to close the same, a stem for the oil-valve guided within the slide-valve and a

spring compressed between the slide-valve and the stem of the oil-valve.

6. The combination in a mixing or generator valve of a main admission-valve, an oil-valve connected therewith, a mixing-chamber in which the oil and air commingled are admitted through ports of the main valve, and a supplemental mixing-chamber connected with the former through one or more openings of restricted size adapted to obstruct the flow and insure a thorough mixture of the oil and air.

7. In a generator or mixing valve, the combination substantially as described of a piston or slide valve constituting the main admission-valve, a spring tending to close the same, an oil-valve positively engaged by said piston-valve during closing movement only when the piston-valve returns under the action of its spring to position to close the inlet to the mixing-chamber, said piston-valve being adapted to move independently of the oil-valve during opening movement, and an adjustable stop acting on the oil-valve during its reverse movement only and arranged as described to limit the extent of movement of said oil-valve when it is free and permitted to open by the piston-valve.

8. In a generator or mixing valve, the combination with the valve-body, of a supplemental cap or shell adjustably mounted thereon, a mixing-chamber formed between said cap or shell and the valve-body, a main admission-valve by which the commingled air and oil are admitted to said mixing-chamber, and air-openings in said shell through which additional air-supply may be admitted directly to the mixing-chamber in amount graduated by the adjustment of said shell.

9. In a generator or mixing valve, the combination of a spider or frame secured within the valve-body between the mixer-valve and outlet, a mixer-valve having a stem guided thereon, a spring bearing at one end against said spider or frame and at the other against the valve so as to keep the same closed, an oil-valve having a shoulder engaged by the mixer-valve and provided with a stem extending down within the stem of the mixer-valve, and a spring within the stem of the mixer-valve tending to unseat the oil-valve.

10. In a generator or mixing valve, the combination substantially as described of the main admission-valve, a spider or frame having a hollow stem upon which the hollow valve-rod is guided, an oil-valve having a valve-rod guided in said frame and in the main admission-valve, a spring tending to open said oil-valve and contained within the said guiding-stem, and an adjustable stop adapted to be engaged by the stem of the oil-valve during its opening movement.

11. In a generator or mixing valve, a valve-casing 1 having an extension of reduced diameter constituting a cylinder for the piston-valve and provided with ports or openings governed by said valve, and an exterior cap

or shell adjustable on said extension and having a skirt or flange overlapping upon the body of the valve and provided with air-openings, said cap or shell being adapted to form 5 a mixing-chamber.

12. In a generator or mixing valve, the combination of the body or casing 1 having an extension of reduced size provided with openings 10 and constituting the cylinder for a 10 piston-valve, a cap or shell adjustable on said extension and having a skirt or flange overlapping upon the body 1, valve ports or openings in the walls of said extension adapted to form admission-ports through which the air

and oil may pass to a mixing-chamber formed 15 by said cap or shell and openings 12 in the body or casing 1 through which the mixture may pass from the mixing-chamber on its way to the outlet.

Signed at New York city, in the county of 20 New York and State of New York, this 4th day of May, A. D. 1901.
